United States Patent Office

Des. 211,437
Patented June 11, 1968

211,437

HANDBAG LOCK OR SIMILAR ARTICLE

David Damast, 22-14 40th Ave.,
Long Island City, N.Y. 11101

Filed Aug. 23, 1967, Ser. No. 8,357

Term of patent 3½ years

(Cl. D87—2)

FIGURE 1 is a front elevational view of handbag lock or similar article showing my new design in closed position.

FIG. 2 is a top view thereof.

FIG. 3 is a side elevational view thereof.

FIG. 4 is an exploded perspective view showing the lock in open position.

I claim:

The ornamental design for handbag lock or similar article, substantially as shown and described.
